UNITED STATES PATENT OFFICE.

LOUIS A. HENNING, OF TOLEDO, OHIO.

WIRE-FENCE-ATTACHING MEANS FOR POSTS.

977,189.

Specification of Letters Patent. Patented Nov. 29, 1910.

Application filed November 3, 1909. Serial No. 525,999.

To all whom it may concern:

Be it known that I, LOUIS A. HENNING, a citizen of the United States, and a resident of Toledo, in the county of Lucas and State 5 of Ohio, have invented a certain new and useful Wire-Fence-Attaching Means for Posts; and I do hereby declare the following to be a full, clear, and exact description of the invention, such as will enable others skilled in the art to which it appertains to 10 make and use the same, reference being had to the accompanying drawings, and to the figures marked thereon, which form a part of this specification.

15 My invention relates to means for attaching the line wires of fences to metallic posts of the trough or channel type; and has for its object the provision of simple, improved and inexpensive means of this class, which 20 is adapted to securely hold the line-wires to a post and at the same time permit free longitudinal contracting and expanding movements thereof relative to the post under different weather conditions.

25 A further object of my invention is the provision of a fence fastening means for posts which is adjustable or capable of swinging in the arc of a circle to adapt it to engage line wires which are spaced at varying distances apart, or for use in connection with wire fences or fabrics of fine or coarse mesh.

35 The construction and arrangement of the parts of the invention are fully described in the following specification, and illustrated in the accompanying drawings, in which,—

Figure 1 is a perspective view of a metallic post adapted and equipped with my invention. Fig. 2 is a side elevation thereof. 40 Fig. 3 is a central longitudinal section of a portion of the same. Fig. 4 is a cross-section of the post on the line $\alpha\alpha$ in Fig. 2, and Fig. 5 is an end view of a slightly modified form of a post embodying the invention.

45 Referring to the drawings, A designates a post adapted for use in connection with my improved line-wire attaching means. This post is of channel or U-shape in cross-section and is shown as comprising the body or central portion 1 and webs or extensions 50 2, 2 which project in the same general direction from the opposite side edges of such body portion and have their outer edges bent laterally or fashioned to form terminal flanges 3, 3, whereby to present flat bearing surfaces to the line wires 4.

The body portion 1 of the post has its outer face centrally formed with a rounded longitudinally extending surface 5 which is shown in Figs. 1, 2, 3 and 4 as being concaved in form, and in Fig. 5 as being convexed in form. This central rounded portion of the post is provided at suitable distances apart longitudinally thereof with apertures 6 for the reception of the stems 65 of wire fastening members 7, which are headed at one end, as at 8, and are intended to have said heads bear against the rounded surface 5 of the post and to have their opposite ends bent around the line wires 4, as 70 at 9, to hold such wires securely to the post.

In order to securely hold the line wires to the post and at the same time to permit them to freely contract or expand under changing weather conditions without liability of bending, weakening or breaking the securing members 7 by the lateral stress to which they are subjected by such action of the wires, the inner face of the heads 8 of the securing members are rounded either in concave or convex form to fit the complementary bearing surfaces 5 of the post. It is apparent that pivotal or swivel joints are thus provided between the post and the heads of the securing members between the webs 2, 2 of 85 the post when the wires have longitudinal movements relative thereto, it, of course, being understood that the perforations in the post are sufficiently large to permit such free pivotal movements of the members. 90 This permissible pivotal action of the securing members is a very important feature, as one of the main difficulties in wire fence construction has been the pulling of the securing means from the post or the loosening 95 or breaking of the same due to the contraction or expansion of the line wires. It is also apparent that the permissible universal pivoted movements of the securing members enables them to be swung vertically or longitudinally of a post as well as laterally thereof to engage the longitudinal wires of fences of different mesh, thus obviating the necessity of positioning the securing members to accurately register with the longitudinal wires of a fence being hung, which wires may be one or more inches apart.

In both of the forms of post shown, the bearing surfaces for the heads of the securing members are disposed within the plane 110 of the inner ends of the webs 2 of the post to permit a counter-sinking of such heads

relative to the contiguous post edges whereby to protect the heads of such members from injury due to animals rubbing against the post or other objects striking the same.

5 I wish it understood that my invention is not limited to any specific construction or arrangement of the parts or formation of the complementary bearing surface of the post and securing members except in so far as such limitations are specified in the 10 claims.

Having thus described my invention, what I claim as new and desire to secure by Letters Patent, is,—

15 1. A channel post having its central portion longitudinally corrugated and provided with rounded bearing surfaces, and a wire fastening means projected through said central portion and having pivotal bearings on 20 said rounded surfaces, substantially as described.

2. A channel post having its central portion perforated and provided with rounded bearing surfaces, and wire fastening means projected through said perforations from the outer side of the post and having heads provided with bearing surfaces which are complementary to and adapted to pivotally seat on the rounded surfaces of the post.

30 3. In combination a channel post having a central longitudinally corrugated portion and webs extending therefrom, a wire fastening member loosely projected through said central portion from the outer side 35 thereof and between the webs and adapted to hold the line wire to the web edges, said central portion and member having complementary concave and convex bearing surfaces adapted to permit a free lateral oscillation of the member relative to the post.

40 4. In combination a post U-shaped in cross-section having a central portion provided with a rounded surface, a wire fastening member projected through said central portion from the outer side thereof between the webs of the post to adapt an end thereof to engage and hold a wire to the outer edges of such webs, the outer end of 45 said member being provided with a head 50 which is rounded on its inner face to adapt

it to present a complementary surface to and seat on the rounded surface of the post to adapt the fastening member to have universal pivotal movements.

5. In combination, a channel post having a central longitudinally corrugated portion and webs extending from opposite sides thereof, a wire fastening member projected inwardly through said portion and having its outer end headed and pivotally seating on one of the ridges of the corrugations within the plane of the outer edges of said central portion, said member having its other end adapted to engage with a wire to hold it to the edges of the flanges, substantially as described.

6. In combination, a channel post having a central portion and webs extending therefrom, said central portion being concaved and having a centrally disposed longitudinal rib provided with a rounded surface and having openings provided therethrough at intervals, wire fastening members projected inwardly through said openings and having their outer ends headed and provided with surfaces complementary to the rounded surface of such rib to provide a pivotal bearing for said member and their inner ends adapted to attach to wires to hold them to the post webs for longitudinal movements relative thereto.

7. A fence post provided with curved bearing surfaces and wire fasteners projected loosely through said surfaces each having at one end a portion correspondingly curved to fit said bearing surfaces.

8. A fence post provided with curved bearing surfaces, and wire fasteners projected loosely through said surfaces, each having at one end a portion correspondingly curved to fit said bearing surfaces to permit universal pivotal movements of the fasteners relative to the post.

In testimony whereof, I have hereunto signed my name to this specification in the presence of two subscribing witnesses.

LOUIS A. HENNING.
